UNITED STATES PATENT OFFICE

157,950

GAME BOARD

Nathan D. Goldstein, Buffalo, N. Y.

Application December 18, 1948, Serial No. 150,240

Term of patent 14 years

(Cl. D34—5)

To all whom it may concern:

Be it known that I, Nathan D. Goldstein, a citizen of the United States, residing at Buffalo, in the county of Erie and State of New York, have invented a new, original, and ornamental Design for a Game Board, of which the following is a specification, reference being had to the accompanying drawing, forming part thereof.

Figure 1 is a plan view of a game board, embodying my new design.

Figure 2 is a side elevation thereof.

I claim:

The ornamental design for a game board, as shown.

NATHAN D. GOLDSTEIN.
